Patented Mar. 29, 1921.

UNITED STATES PATENT OFFICE.

WILLIAM ANDREW MORRISON AND FREDERICK DELIMER LAKE, OF ST. CATHARINES,
ONTARIO, CANADA.

ELECTRIC HEATER.

1,372,823.

Specification of Letters Patent. Patented Mar. 29, 1921.

Application filed August 25, 1919. Serial No. 319,832.

To all whom it may concern:

Be it known that we, WILLIAM ANDREW MORRISON and FREDERICK DELIMER LAKE, both of the city of St. Catharines, county 5 of Lincoln, Province of Ontario, Canada, have invented certain new and useful Improvements in Electric Heaters, of which the following is the specification.

Our invention relates to improvements in 10 electric heaters, and the object of the invention is to devise a simple, cheap, compact, highly efficient form of electric heater in which the heating element may be quickly and easily removed for the purpose of re- 15 pair without damage to any part of the heater and it consists essentially of the following arrangement and construction of parts as hereinafter more particularly explained.

20 Figure 1, is a side elevation of our heater. Fig. 2, is a vertical sectional view through Fig. 1.

Fig. 3, is a cross sectional view in line "x" — "y".

25 Fig. 4, is a cross sectional view in line "x¹" — "y¹" Fig. 2.

Fig. 5, is a cross sectional view in line "x²" — "y²" Fig. 2.

Fig. 6, is the end of the heater looking 30 at the bottom.

In drawings like characters of reference indicate the corresponding parts in the various figures.

1 indicates the outer casing which is cylindrical in form and which is provided at 35 its upper end with a head 2 having an outlet orifice 3 from which leads the discharge pipe 4. At the lower end the casing 1 is provided with a head 5 having a circular 40 orifice 6 around the edge of which extends a rabbet groove 7. 8 is an inner cylinder provided with a closed upper end 9. The lower end of the cylindrical casing fits in the rabbet groove 7. The interior diameter 45 of the casing corresponds to the diameter of the orifice 6. A space 10 is formed between the outer and inner casing through which the water to be heated passes to the outlet pipe 4. 11 is an inlet pipe which is 50 secured in the orifice 12 which is formed preferably in the reinforced portion 13 of the casing 1. 14 is a heating element. The heating element 14 comprises a central core 55 which is preferably formed of soap stone 15 or other material adapted to absorb and re-

tain heat to a maximum extent. The core 15, as shown in the drawing, comprises a circular head 16 at the lower end from which extends centrally a stem portion 17. 18 is an enlargement which is formed above 60 the stem 17 and integral therewith. The enlargement 17 is provided with longitudinal grooves 19 spaced an equal distance apart around the surface of the enlargement. Above the enlargement 18 is formed 65 a reduced portion 20. Above the reduced portion 20 is another enlargement 21 similar to the enlargement 18 provided with longitudinal grooves 22 in alinement with the longitudinal grooves 19. Above the enlargement 20 is another reduced portion 23 similar to the reduced portion 20 and above the reduced portion 23 is another enlargement 24 provided with longitudinal grooves 25 in alinement with the grooves 19 and 22 70 of the enlargements 18 and 21. Between the enlargements 21 and 24 the reduced portions 20 and 23 are provided outwardly extending annular flanges 26 and 27. The flanges 26 and 27 are provided with a series 80 of orifices 29 which are in alinement with the base portion of the grooves 19, 22 and 25. 28 and 29 are coiled wires which pass upwardly at each side of the core 15 of the heating element and are identical in form. 85 One end of each wire 28 and 29 is secured by suitable binding screws to the head 16 and from thence pass upwardly through the longitudinal grooves 19 of the enlargement 18 then through the orifice 29 of the flange 90 27, through the groove 22 of the enlargement 21, then through the orifice 29 of the annular flange 27, then through the longitudinal groove of the enlargement 24, then through the longitudinal groove 25 of the 95 enlargement 24. The coil wires then return downward through the next successive groove 25, through the orifice 29 of the flange 27, groove 22 of the enlargement 21, orifice 29 of the flange 26 and groove 19 100 of the enlargement 18. The coil wires again return upward through the next successive grooves 19, 22 and 25 and the orifice 29 of the upper end of the core, when it again returns downward through another set of 105 grooves 25, 22 and 19 and is secured at its opposite end to the head 16. Although we have described the core formed as above and the winding wound as above it will of course be understood that the wire winding can be 110

wound upon the core in any desired way. For example in the core spiral grooves may be formed extending from end to end the windings of the element being held in these spiral grooves and we therefore do not desire to limit ourselves to any particular method of forming the core and winding the wire thereon. The lower end of the casing 1 formed by the cap 5 is provided 10 with a pair of headed screws 30 and 31. 32 is an end closure provided with an annular flange 33 having arc-shaped slots 34 and 35 formed therein and terminating at their opposite ends in the enlargements 36 and 37 15 through which the heads of the screws 30 and 31 are adapted to pass. When the heads of the screws are passed through the enlargements 36 and 37 of the end closure 32 the end closure is given a slight turn thereby locking the closure in position. The body of the closure 32 is cylindrical in form and is provided at its lower end with an insulating disk 38 which is secured to the lower end of the closure and is provided 20 with orifices 39 through which the lead wires pass to be connected to the windings 28 and 29. When the heater is to be used for heating water the current is turned on to pass through the windings. The heat 25 generated by the windings is absorbed by the soap stone core and such absorbed heat is retained for a long period of time. It will therefore be understood that in heating a certain amount of water it will be 30 only necessary to turn on the current for a short period of time in order to raise the core to the required temperature. The current is then turned off, the heat radiating from the core serving to complete the heating 35 of the water and to maintain the water at the required temperature for a considerable period of time. Although we have described our heater as applied to the heating 40

of water it will of course be understood that the heating element comprising the soap stone core and windings may be utilized for various purposes such as the heating of electric irons and electric stoves, &c., furthermore the outer casing may be dispensed with and the heating device passed 45 through and secured in an orifice formed in the wall of the water container and will serve to heat a body of water therein. 50

In case of repair it will be readily seen that all that is necessary to do is to give 55 the closure 32 a slight turning movement when it may be withdrawn from the end of the casing 1. When this is completed the heating element 14 may be slipped from the interior of the casing, repaired and 60 slipped back into position, the closure 32 being again placed in position. From this description it will be seen that we have devised an electric heater which is cheap to construct and in which the heating element 65 may be gotten at, at any time for the purpose of repair, in which the current consumed will be economized and which will maintain its temperature for a considerable period of time after the current has been 70 turned off.

What we claim as our invention is—

A heating element comprising a core of heat absorbing and retaining material provided with a plurality of grooved enlargements each having the grooves thereof registering with the grooves of adjacent enlargements, flanges between said enlargements provided with apertures corresponding in number and position to said grooves, 75 and a winding for the core passing through the said apertures and disposed in said grooves. 80
